DESIGN FOR A MEDALLION SCARF-RING.

The Schedule referred to in these Letters Patent and making part of the same.

TO ALL WHOM IT MAY CONCERN:

Be it known that I, RALPH S. JENNINGS, of New York, in the county of New York, and State of New York, have originated and designed a new Design for Scarf-Rings; and I do hereby declare that the following is a full, clear, and exact description of the same, reference being had to the annexed drawings, making a part of this specification, and to the letters and figures of reference marked thereon.

Figure 1, of the drawings, is a representation of an external view of my scarf-ring.

My invention and design consist in constructing a scarf-ring with a likeness of Honorable Schuyler Colfax attached thereto, in the form and manner represented on the drawings.

What I claim as my invention, and desire to secure by Letters Patent, is—

The design for a scarf-ring, as described and shown.

In testimony that I claim the above, I have hereunto subscribed my name in the presence of two witnesses.

RALPH S. JENNINGS.
